UNITED STATES PATENT OFFICE.

JAFEW S. VAN BUREN, OF ALBANY, NEW YORK.

COMBINED COAL AND GAS RANGE.

1,296,237.

Specification of Letters Patent.

Patented Mar. 4, 1919.

Application filed October 13, 1915. Serial No. 55,651.

To all whom it may concern:

Be it known that I, JAFEW S. VAN BUREN, a citizen of the United States, and a resident of Albany, county of Albany, State of New York, have invented certain Improvements in Combined Coal and Gas Ranges, of which the following is a specification.

My invention relates to certain improvements in combined coal and gas ranges.

One object of the invention is to construct the range so that the oven can be heated by a burner located outside of the oven and can be exposed or covered by the hearth plate.

A further object of the invention is to provide the oven door with flue passages communicating with the interior of the oven and with the ash pit of the coal section of the stove.

A still further object of the invention is to provide a damper for checking the draft from the coal section, as well as to provide a damper for directing the passage of the products of combustion either to the flue or around the oven.

My invention relates to certain improvements in the burner for heating the oven.

These objects and other advantageous ends I attain in the following manner, reference being had to the accompanying drawings in which:

Figure 1 is a transverse sectional view of a combined gas and coal stove illustrating my invention, the section being on the line *a—a*, Fig. 2;

Fig. 2 is a sectional view on the line *b—b*, Fig. 1;

Fig. 3 is an enlarged sectional view, similar to Fig. 1, of the front part of the stove illustrating certain details of the invention;

Fig. 4 is a sectional plan view on the line *c—c*, Fig. 3;

Fig. 5 is a view, similar to Fig. 3, showing the lower portion of the stove and the hearth drawn out to expose the gas burner;

Fig. 6 is a detached perspective view of the front cover plate for the burner chamber;

Fig. 7 is an enlarged inverted perspective view of the hearth plate; and

Fig. 8 is a reduced front view of the oven door.

Referring to the drawings, 1 is the top plate of the stove. 2 is the oven. 3 is the burner space formed by the casing 4. In this burner space is placed either the burners for manufactured gas or for natu-

ral gas, as the case may be, the burners being supplied from a pipe 5 extending along the front of the stove arranged directly below the top plate. 6 is the top plate of the oven spaced from the bottom of the casing 4 to form a flue 7 communicating with the fire box 8 of the coal section of the stove and the down flue 9 which leads around the oven and communicates with the under flue 10. 11 is the back flue which communicates with the bottom flue 10 under the oven and with the chimney. 12 is a pivoted damper which can be opened to allow the products of combustion from the coal section of the range to pass directly from the flue 7 without passing around the oven. This damper is controlled in the ordinary manner, in the present instance from the front of the stove. 13 is a sliding damper, in the present instance, having a hand hold 14 projecting over the top plate of the stove and when this damper is opened it allows air to pass from the gas burner chamber directly into the flue leading to the chimney so as to check the draft from the coal section of the range whether the damper 12 is opened or closed. The opening can be made of any area desired by merely sliding the damper in its ways.

15 is the oven door hinged in the ordinary manner and made as clearly shown in Fig. 8 having, in the present instance, a central recess 16 in which the thermometer for indicating the temperature of the oven is located. 17 is the hearth plate located under the oven door and 18 is the front cover plate for the oven burners. The bottom 19 of the oven terminates some distance back of the inner edge of the door, as clearly shown in Fig. 3. This allows for the location of the burner 20 in the space below the oven at the front so that when the hearth plate is shifted to the position illustrated in Fig. 5, the flame from the burner 20 will enter the oven between the door and the bottom plate. When the hearth plate is forced in, it closes this space, as illustrated in Fig. 3, so that the gas cannot be used until the hearth plate is withdrawn, as illustrated in Fig. 4.

38 is a deflecting plate located above the bottom of the oven. The front edge of this plate comes in contact with the oven door and rests on a flange 39 on said door and stops short of the rear of the oven so that the heat from the burner is carried to the

rear of the oven before being distributed through the oven.

The burner may be of any type desired and is preferably shaped as shown by dotted lines in Fig. 4, having the usual bell end 21 into which the gas pipe extends and in which are the openings for supplying the burner with air. The amount of air can be controlled by the usual damper. The gas pipe 10 enters this burner in the ordinary manner and the burner has a primary section 22 and a secondary section 23. In the latter section is a series of burner openings 24 through which passes the gas to be ignited. This 15 construction insures a thorough mixture of gas and air before it escapes from the burner.

It will be noticed, upon referring to Figs. 3 and 5, that the section 23 is made eccentric, being thicker at the side where the burner openings are than at the opposite side. This enables me to provide an extended escape passage for the gas without providing nipples or other extensions. The 25 burner cover plate 18 is made as clearly shown in Fig. 6 and has a flange 25 at each side on which rests the hearth plate 17. This hearth plate has undercut lugs 26 which extend under this flange and hold the 30 hearth plate from tipping. At the front of the cover plate 18 is an extension 18^a with which engage the lugs 27 and 28 on the under side of the hearth plate so that when the hearth plate is closed the lug 27 is back 35 of the extension 18^a, preventing the outward movement of the hearth plate. When the hearth plate is in the extended position the lug 8 is in front of the extension 18^a, preventing the hearth plate from being 40 pushed toward the oven to accidentally cover the burner openings. The hearth plate is raised when shifted in either of its two positions. The rear end of the hearth plate has a flange 29 which extends over 45 the section 23 of the burner and covers the openings 24 when the burner is not in use. The side members 30 of the burner cover plate 18 are recessed at 31 and the burner rests in these recesses. The recess at one 50 end of the plate is larger than the other as the large end receives the burner and the other section receives a lug on the end of the burner, as clearly shown by dotted lines, Fig. 3, but it will be understood that the 55 burner may be held in place in any suitable manner without departing from the essential features of the invention.

It is desirable to provide means for indicating whether or not the oven burner is 60 ignited and I polish the upper surface of the hearth plate and so locate the bottom of the door that it will be some distance above the hearth plate. When the gas from the burner is ignited the flame will be reflected 65 from the hearth plate under the door and a

person using the range can at any time see the flame reflected in the polished surface of the hearth and can detect any unevenness in the burning of the gas without the necessity of opening the oven door and interfering with the baking. 70

In order to provide an oven in which the heat is evenly distributed, I form a passage in the oven door by shaping the oven door as indicated in Figs. 3 and 4, and locating 75 a plate 32 at the back of the oven door. This plate is spaced from the body portion 15 of the door so as to form a flue or passage 33. When the door is closed the lower portion of this flue communicates through a 80 passage 34 with the ash pit 35 of the coal section of the stove and in the flue 33 is a deflecting plate 36, Fig. 8, and in the upper portion of the plate 32 are openings 37. These openings are graduated in size, as 85 shown in Fig. 8, so that the heated air will be drawn evenly from the oven and discharged into the ash pit. The deflector 36 causes the heated air to pass through the flue 33 entirely over the surface of the door 90 so as to insure the proper heating of the door and thus make the heated air in the oven at the door substantially the same temperature as the air in the other parts of the oven. In ovens of the ordinary construction, the 95 oven is coolest at the door and, consequently, the baking is more or less uneven.

This construction of the oven door is used to advantage either with the coal section of the range or with the gas section. When the 100 coal section is in use the heated air from the oven passes into the ash pit under the grate and aids materially in the proper combustion of the fuel. When the gas range is in use, it merely relieves the oven of any unspent gases which pass into the closed ash pit of the coal section and from this ash pit through the flue to the chimney so that it acts as a ventilator to a certain extent for 105 the oven. 110

While I have described my invention in connection with a combined gas and coal range, it will be understood that the arrangement for heating the oven and the arrangement of the oven door may be used 115 in connection with a gas or coal range, as well as with a combined range without departing from the spirit of the invention.

The damper 13 is also used when the burners are burning natural gas and where 120 the top plate is sealed to carry off the spent gases from the chamber formed by the casting 4.

I claim:

1. In a combined coal and gas range, the 125 combination of an oven; flues surrounding the oven; a fuel chamber at one side of the oven communicating with the flues; a gas burner extending longitudinally under the oven near the forward end thereof; a door 130

for the oven extending beyond the burner; a sliding hearth plate on a line substantially with the bottom of the oven and arranged to extend over the burner and close the 5 burner opening leading to the oven, the parts being so arranged that the oven gas burner can be used with or without the coal fuel.

2. In a combined coal and gas range, the 10 combination of an oven; a fire pot at one side of the oven; flues extending around the oven and communicating with the fire pot; a door for the oven having flue passages therein, the bottom of the oven terminating 15 some distance back of the oven door; a deflecting plate located above the bottom of the oven and terminating short of the rear

thereof, the oven door having an internal, horizontal flange near its lower edge over which the deflecting plate extends; a sliding 20 hearth for the oven and extending under the oven door; a burner extending longitudinally substantially the full width of the oven and under the inner end of the sliding hearth so that when the sliding hearth is 25 moved out there will be communication between the burner space and the oven so that the burner can be used to heat the oven and when the hearth is pushed in the burner is cut off from the oven.

JAFEW S. VAN BUREN.
